BOTTLE

Elwyn R. Gooding, Ann Arbor, Mich., assignor to Ex-Cell-O Corporation, Detroit, Mich.

Filed Apr. 1, 1964, Ser. No. 79,301

Term of patent 14 years

(Cl. D58—6)

FIG. 1 is a side elevational view of a bottle, showing my new design;

FIG. 2 is an end elevational view thereof;

FIG. 3 is a top plan view thereof;

FIG. 4 is a bottom plan view thereof; and

FIG. 5 is a cross-sectional view thereof taken on line 5—5 of FIG. 1.

The dominant features of my design reside in the portions shown in full lines.

I claim:

The ornamental design for a bottle, as shown and described.
